SIDING CORNER CONSTRUCTION

Leslie S. Odell, Montreal, Quebec, Canada, assignor to Bird & Son, Inc., East Walpole, Mass.

Application May 5, 1939, Serial No. 271,837
In Canada April 20, 1939

4 Claims. (Cl. 20—5)

This invention relates to corner constructions for use in connection with the application of brick, stone, or tile simulating siding to the walls of building structures; and it comprises metal corner members shaped to fit over and cover those opposing ends of the siding sections which meet at the corners of the building structure to which the siding is applied. Each corner member has applied directly to its outer surface an initially plastic coating, such as paint or enamel, into which granular particles are pressed to provide a surface pattern composed of brick, stone or tile simulating areas and intervening mortar joint simulating areas which are matched with corresponding areas of the surface pattern presented by the underlying siding sections.

The method of surfacing the metal corner members to match the surface pattern of the underlying siding sections is subject to considerable variation. In the example selected for illustration the brick or stone simulating areas of the corner members are formed of spaced patches of granular material but the intervening mortar colored areas are formed simply by painting the outer surface of the metal to match the color of the granular particles forming the mortar joint simulating areas of the siding sections. It is contemplated, however, that the mortar joint simulating areas of the corner members may also be formed by patches or bands of granular material of a color contrasting with the granular patches forming the brick, stone or tile simulating areas. It is also contemplated that both the joint simulating areas and the brick, stone or tile simulating areas of each corner member may be simply painted on the outer surface of the metal in colors matching corresponding areas of the siding sections.

The aforesaid metal corner members are shaped, preferably by a pressing operation, to provide relatively wide elevated areas which are surfaced in simulation of brick, stone or tile elements and relatively narrow depressed areas which are surfaced in simulation or mortar joints. This shaping of the corner members is particularly useful in connection with certain types of brick, stone or tile simulating siding in which the mortar joint simulating areas are sunk a substantial distance below the brick, stone or tile simulating areas.

In some instances the surfacing of the metal corner members with granular particles may be omitted. For example, if the metal corner members are made of copper the elevated areas thereof may be simply tinted to match, as closely as

possible, the brick, stone or tile elements of the underlying siding sections.

The invention further provides improved means for securely anchoring the corner members to the building structure to which the siding is applied, said means serving to press the corner members tightly against the outer surfaces of the underlying siding sections.

The corner members mentioned herein are especially adapted for use in connection with siding of the type comprising a comparatively thick and rigid fibrous base, a sheet of water resistant felt adhesively secured to the weather side of the base and a weather resistant surface comprising granular particles embedded in asphalt at the outer side of the felt sheet and arranged to form a definite ornamental surface pattern in simulation of a brick, stone or tile surface. Examples of such siding are disclosed in my prior Patents 2,021,577, 2,021,578 and 2,021,579 granted Nov. 19, 1935. Said corner members may also be used to advantage in connection with the application of flexible siding sections consisting simply of a flexible sheet of water resistant roofing felt having granular particles arranged on the weather side in simulation of a brick, stone or tile surface.

In the further description of this invention reference will be had to the accompanying drawings, in which:

Fig. 1 is a perspective view showing the manner in which the corner members provided in accordance with my invention are applied to the siding sections at the corners of a building structure.

Fig. 2 is a view showing the assembled siding sections and corner member in front elevation.

Fig. 3 is a top plan view of the assembly appearing in Fig. 2.

Fig. 4 is a perspective view of the corner member as it appears after being provided with a brick, stone or tile simulating surface.

Fig. 5 is a longitudinal sectional view taken along the line 5—5 of Fig. 4.

Fig. 6 is a transverse section along the line 6—6 of Fig. 4.

Figs. 7 and 8 are perspective views showing the corner member as it appears prior to being provided with the ornamental surfacing shown in Fig. 4.

Referring more particularly to the drawings, 5 and 6 designate two angularly related building walls meeting in a corner 7. A section 8 of brick simulating siding is shown applied to the outer surface of wall 5 in horizontal alignment with a

similar siding section 9 applied to the outer surface of wall 6. These siding sections are preferably made in accordance with my previously mentioned patents, each section being surfaced by differently colored particles of granular material arranged to present brick simulating areas 10 and intervening mortar joint simulating areas 11. It will be noted that the several courses of brick colored areas and the horizontal joint simulating areas appearing on each section are horizontally aligned with corresponding areas of the companion section.

The ends of the siding sections which meet at the corner 7 are covered by a metal corner member 12. This member is bent along its longitudinal center to provide two angularly related side portions 13 and 14 having their free longitudinal edges formed to provide rib-like projections 15. The corner member is applied with side portion 13 overlying siding section 8 and side portion 14 overlying siding section 9. It is secured in place by fastening screws 16 which serve to embed the ribs 15 in the siding sections as shown to advantage in Fig. 3. Screws 16 penetrate wall 6 and are given additional anchorage by threaded engagement with openings 17 formed in a metal anchoring plate 18 which is shaped to fit corner 7 and is nailed or otherwise fastened to the outer surfaces of walls 5 and 6.

The metal corner member 12 is surfaced to provide brick simulating areas 20 and horizontal mortar joint simulating areas 21 matching the brick simulating areas 10 and the horizontal mortar joint simulating areas 11 of the underlying siding sections. In the present instance the brick colored areas 20 are formed by suitably colored particles of granular material 23 (Fig. 6) embedded in an initially plastic paint, enamel or other coating layer 24 applied directly to the metal of the corner member. The mortar joint simulating areas 21 are formed simply by a paint or enamel coating 25 (Fig. 5) of a color closely approximating the color of the granular particles forming the joint simulating areas 11 of the siding sections. The metal corner member may be prepared for the reception of the paint or enamel coating by conventional galvanizing and pickling operations.

The metal corner member is shaped, preferably by a pressing operation, so that its outer surface presents raised brick simulating portions A (Fig. 7) and depressed mortar joint simulating portions B. The mortar joint simulating enamel 25 is applied to the depressed portions B as shown in Fig. 5 while the coatings 24 and brick simulating granules 23 are applied to the raised brick simulating areas A. The raised portions A and the depressed portions B are dimensioned to match the width of the brick and horizontal joint simulating areas of the siding sections as shown to advantage in Fig. 2. The depressed portions B are provided with perforations C through which the fastening screws 16 are passed.

If the metal corner member appearing in Fig. 7 is made of copper, I may omit the application of granular surfacing material and merely tint the exposed surface of the corner member to match the brick, stone or tile elements of the underlying

siding. The rib like projections 15 may also be omitted from the corner members as indicated in Figures 7 and 8.

Having thus described my invention, what I claim is:

1. In combination, a building structure including angularly related walls meeting in a corner, brick, stone or tile simulating siding applied to the outer surface of said walls, a metal corner member shaped to fit over and cover those opposing ends of the siding sections which meet at said corner, said corner member being surfaced to provide a masonry simulating surface pattern matching that of the underlying siding sections, an anchoring plate secured to said walls to fit over the corner formed thereby, said anchoring plate being interposed between said walls and said siding and fastening screws passing through said corner member and said anchoring plate and into one of said walls, said fastening members being in threaded engagement with openings formed in said anchoring plate.
2. In combination, a building structure including angularly related walls meeting in a corner, masonry simulating siding panels applied to the outer surface of said walls, a metal corner member shaped to fit over and cover those opposing ends of the side panels which meet at said corner, said corner member being surfaced to provide a masonry simulating surface pattern matching that of the underlying side panel, a metal anchoring plate secured to said walls and shaped to fit over the corner formed thereby, said anchoring plate being interposed between said walls and said siding and fastening members securing said corner member to said anchoring plate.
3. In combination, a building structure including angularly related walls meeting in a corner, masonry simulating siding panels applied to the outer surface of said walls, a metal corner member shaped to fit over and cover those opposing ends of the siding panels which meet at said corner, said corner member being surfaced to provide a masonry simulating surface pattern matching that of the underlying siding panels, an anchoring plate interposed between said siding panel and said wall and secured to the latter and fastening members securing said corner member to said anchoring plate, said fastening member passing through said corner members and having threaded engagement with said anchoring plate.
4. In combination, a building structure including angularly related side walls meeting in a corner, siding panels applied to the outer surface of said walls, a metal corner member comprising a bent strip of metal presenting angularly related side portions overlying and engaging those opposing ends of the siding panels which meet at said corner, a metal anchoring plate secured to said walls and shaped to fit over the corner formed thereby, said anchoring plate being interposed between said walls and said siding and fastening members securing said corner member to said anchoring plate.
